US0D1072885S

(12) **United States Design Patent** (10) **Patent No.:** **US D1,072,885 S**
(45) **Date of Patent:** **** Apr. 29, 2025**

(54) **FLUID END**

(71) Applicant: **GD Energy Products, LLC**, Tulsa, OK (US)

(72) Inventor: **Konner Casey Kay**, Broken Arrow, OK (US)

(73) Assignee: **GD ENERGY PRODUCTS, LLC**, Tulsa, OK (US)

(**) Term: **15 Years**

(21) Appl. No.: **29/863,578**

(22) Filed: **Dec. 20, 2022**

(51) LOC (15) Cl. **15-04**

(52) U.S. Cl.

USPC **D15/21; D15/7**

(58) **Field of Classification Search**

USPC D15/5, 7, 21, 9.1, 17, 28, 132, 138, 151;

D23/233, 235, 237, 245, 259, 269;

D12/218

CPC F16K 1/42; F16K 27/0254; F04B 1/0538;

F04B 1/0461; F04B 1/0448; F04B 1/16;

F04B 37/12; F04B 52/22; F04B 53/22;

F05B 2260/301; Y10T 137/7838; Y10T

137/87885; F16H 61/30; E21B 44/06;

B29C 44/1271

(57) **CLAIM**

The ornamental design for a fluid end as shown and described.

DESCRIPTION

FIG. 1 is a rear perspective view of a fluid end;

FIG. 2 is a front perspective view of the fluid end of FIG. 1;

FIG. 3 is a rear view of the fluid end of FIG. 1;

FIG. 4 is a front view of the fluid end of FIG. 1;

FIG. 5 is a first side view of the fluid end of FIG. 1;

FIG. 6 is a second side view of the fluid end of FIG. 1;

FIG. 7 is a top view of the fluid end of FIG. 1; and,

FIG. 8 is a bottom view of the fluid end of FIG. 1.

Any portions shown using dashed lines are for illustrative purposes only and form no part of the claimed design.

1 Claim, 8 Drawing Sheets
